UNITED STATES PATENT OFFICE.

GEORGE L. BATCHELDER, OF BLOOMINGTON, ILLINOIS.

HOLDER FOR ELECTRIC LAMPS AND HOODS.

SPECIFICATION forming part of Letters Patent No. 442,472, dated December 9, 1890.

Application filed May 5, 1890. Serial No. 350,608. (No model.)

To all whom it may concern:

Be it known that I, GEORGE L. BATCHELDER, of Bloomington, in the county of McLean and State of Illinois, have invented a new and Improved Holder for Electric Lamps and Hoods, of which the following is a full, clear, and exact description.

My invention relates to improvements in devices for suspending electric lamps and hoods; and the object of the invention is to provide a device by means of which the lamp and hood may be securely suspended and by means of which the lamp or the hood, or both together, may be conveniently lowered by a single rope.

To this end my invention consists in certain features of construction and combinations of parts, which will be hereinafter more fully described, and then pointed out in the claims.

Reference is to be had to the accompanying drawings, forming a part of this specification, in which similar letters of reference indicate corresponding parts in all the figures.

Figure 1 is a vertical section showing the suspending mechanism in front elevation and with the lamp and hood in an elevated position. Fig. 2 is a broken vertical section through the hood, showing the lamp partially lowered from the hood. Fig. 3 is a vertical section through the hood, showing the lamp raised in the hood and with the lamp-hooks about to engage the suspending-hooks. Fig. 4 is a side elevation of the suspending mechanism with the hood removed. Fig. 5 is a detail view, partially in section, of the hood-hook and the slide upon which the hook may rest. Fig. 6 is a detail perspective view of the device for detaching the lamp-hooks, and Fig. 7 is a detail view showing the detaching device for the hood-hook.

The hollow block A is provided with suitable suspending-eyes a, with an opening A' at one end and an opening A² upon the bottom, a grooved pulley B, pivoted centrally in the block over which runs the cord C, by which the hood and lamp are suspended and operated, as described below, and a guard d, suspended by a spring d', to limit the upward movement of the rod H. The block is also provided with a hook a' upon one side near the bottom opening to engage the hood-hook, as hereinafter described, and a spring

b, fixed to the wall of the block above said hook, to hold the hood-hook in engagement therewith, and to also serve as a detaching device, as described below. The spring b is composed of two similar parallel members having inwardly-projecting beveled portions b' and an enlarged opening b² above the said beveled portions, so that when the hood-hook H' is raised through the opening b² and then lowered said hook will strike upon the beveled portions b' and be guided through the lower opening of the block A.

The hood D is of the usual construction, and has fixed in its upper portion a vertical hang-board D', to which the lamp-hanging mechanism is affixed. Supported above the hood D is a cross-bar E, upon which the line-wires are supported in the usual manner, and projecting through said cross-bar and into the hood is a tube F, which vertically aligns with a sleeve F' below the same. The sleeve F' is provided upon its front side with a vertical slot F², extending from the bottom of the sleeve about half-way up the same, said slot being wider near the bottom, and the lower end of the sleeve F' being beveled upon each side, so that the sleeve terminates in a point F³ upon the back portion of the sleeve.

The suspending-rod G is vertically movable in the sleeve F', the upper end of said rod being attached to the cord C, so that by pulling upon the cord C the rod will be raised and by loosening the same it will be lowered. The rod G is provided near its upper end with a laterally-projecting lug G', which engages the slot F² of the sleeve F' and guides the rod so that the lamp-connections will assume their proper polarity when the rod is elevated, as hereinafter described. The rod G has fixed to its lower end a socket G² of the usual form and adapted to hold an incandescent lamp; but it is obvious that instead of providing an incandescent-lamp socket any form of arc lamp may be attached to the rod.

Extending through the top of the hood D and through the cross-bar E parallel with the tube F is a tube e, in which the suspending-bar H is vertically movable, both of said tubes being formed in the case H'. The suspending-bar H is formed at its upper end into a hook H', said hook being provided with side

lugs h' , extending laterally from the body of the hook so as to engage the spring members b' , as above described, and said bar is provided with an angular bend H^2 below the lower end 5 of the sleeve e , which limits the upward movement of the bar and enables the hood to be suspended thereby. A slide J is suspended in a sleeve K immediately below the end of the bar H , said slide being vertically movable in the sleeve K and having an enlarged upper end J' , suitably insulated from the bar H to limit its downward movement in the sleeve, an enlarged lower end J^2 to limit its upward movement in the sleeve, and a depending lip J^3 to engage the end of the lamp-hook rods M , as hereinafter described. The sleeve K is provided near the top with a flat plate K' , which is pivoted upon the hang-board D' , and suspended above the plate K' 15 is an inverted-U-shaped spring K^2 , the members of which press against the sides of the plate K' , and so normally hold the plate K' and sleeve K in a vertical position.

A stop J^4 , similar to the slide J , is fixed to 5 a plate J^5 , and said plate is suspended upon the hang-board D' opposite the sleeve K and slide J and in horizontal alignment therewith, said stop being held in a vertical position by a spring K^2 , which is similar to the spring already described, and the members of which press against the sides of the plate J^5 .

Fixed to the hang-board D' , near the lower edge thereof and upon opposite sides of the suspending-rod G , are the plates L , which project below the lower edge of the hang-board D' , and which are provided with inwardly-projecting hooks L' , adapted to hold the lamp, as described below. The said plates are connected with the line-wires L^2 , and the current passes through the plates and hooks to the lamp.

Pivoted upon the upper ends of the plates L are the angular plates g , said plates being pivoted near their lower ends and having their upper ends provided with spiral springs h , which are fixed to the hang-board D' above the ends of the plates g , and which tend to pull the upper ends of the plates into an elevated position. The plates g are provided with laterally-extending portions g' , which extend diagonally downward above the hooks L' , said portions g' having their lower ends formed into two similar members g^2 , with inwardly-projecting portions g^3 beveled upon their upper surface, and a large central opening g^5 , to permit the passage of the lamp-hook rods through the same. The plates L and g are connected by suitable shunt-wires f to shunt the current when the lamp is removed. The plates g are also provided upon their inner upper edges with beveled portions g^4 , which engage the brushes i , fixed to the plates i' , said plates being attached to the hang-board D' above the plates g . The plates i and the plates L are connected by wires i^2 ,

thus forming a closed circuit when the lamp is removed.

The lamp-socket G^2 has attached to the upper edge thereof, upon opposite sides, the 70 upwardly-projecting rods M , each rod having upon its outer edge a depending hook M' , adapted to engage the hook L' of the plates L when the lamp-socket is raised and be thereby suspended. The sides of the hooks 75 M' project laterally beyond the rods M , as shown in Fig. 4. The rods M are pivoted at their lower ends to the bifurcated frames M^3 , which are properly insulated upon the socket G^2 and project into the interior of the same 80 in the usual manner. The rods M are pressed outwardly by the springs M^2 , which press against the backs of the rods M . The lower portions of the rods M extend below the bifurcated frames M^3 and are formed into inwardly-extending arms M^2 , the arms M^2 and frames M^3 being connected by suitable shunt-wires m .

The device is operated as follows: The block A is suspended upon a suitable support, as 90 described, and to raise the hood and lamp the operator pulls upon the free end of the cord C , and thus raises the hood. The bar H will enter the lower opening A^2 of the block A , and the hook H' will pass between the springs b and hook a' , and the hook H' of said bar will engage the hook a' , thus suspending the hood. To release the hood, drop the lamp out of the hood, as described below, then draw it back, keeping the rope tight, which will hold 100 the rod M against the slide J , and raise the suspending-bar H till the hook H' passes through the opening b^2 between the members of the spring b , and the cord C is slackened. The hook H' will then drop upon the beveled 105 portions b' of the springs b and will be thereby guided by the lugs h' through the lower opening of the block. The hood being heavy, it is necessary to pull harder upon the cord to release the hood than to release the lamp. 110 The hood being suspended, as described, and the lamp being lowered, the lamp is suspended in the hood as follows: By pulling upon the free end of the cord C the rod G , socket G^2 , and the lamp suspended therein will be 115 raised, as described. The upper end of the rod G will enter the sleeve F' and the lug G' will enter the slot F^2 of the sleeve F' , thus bringing the lamp-connections into their proper positions. As the rod G is raised, the 120 ends of the rods M pass between the members g^2 of the plate g and come in contact with the lower ends of the slide J and stop J^4 , thus preventing the lamp from being raised farther. The cord C is then slackened and 125 the hooks M' drop upon the hooks L' , thus suspending the lamp. The slide J and stop J^4 will then resume their normal position, and to release the lamp the operator pulls upon the cord C , as before. The ends of the rods M 130 pass upwardly through the opening g^5 of the plate g , and when the operator slackens the

cord C the laterally-projecting sides of the descending hooks M' strike upon the beveled portions g³ of the plate g, and the hooks M' are thereby prevented from engaging upon the hooks L', thus allowing the lamp to be lowered.

Having thus described my invention, I claim as new and desire to secure by Letters Patent—

10 1. A hood and lamp holder consisting, essentially, of a hollow block having means for attachment to a support and having an opening in the side and bottom thereof, an inwardly-projecting hook fixed to the wall of the block near the bottom opening, a spring-guide fixed in the block and extending below said hook, a grooved pulley pivoted in the block, a cord passing through the openings of the block and over said pulley, having one end 15 thereof connected with the hood, as described, and a bar suitably attached to the hood and having its upper end projecting above the same and formed into a hook to enter the block and engage the hook therein, substantially as described.

2. In a hood and lamp holder, the combination, with a hook on the support and a sliding bar on the hood provided with a hook having laterally-extending lugs, of a spring-guide extending over the hook provided with a central opening and inwardly-extending beveled portions, substantially as described.

3. In a hood and lamp holder, the combination, with a hook on the support and a sliding bar on the hood provided with a hook having laterally-extending lugs, of a spring-guide extending over the hook provided with a central opening and inwardly-extending beveled portions, and a slide pivoted in the hood adapted 35 to engage the sliding bar and to be engaged by an arm of the holder, substantially as described.

4. The combination, with a hood provided with a guide-sleeve, supporting-hooks, pivoted plates having opposite members provided with inwardly-extending beveled portions and extending over the supporting-hooks, and pivoted spring-actuated stop-rods, of a lamp-socket provided with pivoted arms having hooks extending laterally beyond the arms, substantially as described.

5. In a hood and lamp holder, the combination, with a suitable suspending-pulley, of a hood suspended therefrom and having a vertical hang-board fixed therein, a vertical sleeve centrally fixed to said hang-board, said sleeve having a vertical slot therein and a projecting terminal point upon the lower end opposite said slot, said sleeve opening through 55 the top of the hood, a lamp-suspending rod adapted to move vertically in said sleeve, having a laterally-projecting lug thereon to engage the slot of the sleeve and guide the rod, having its upper end attached to a suitable cord extending over the suspending-pulley and having its lower end suitably fixed to a lamp-socket, upwardly-extending spring-

actuated hooks fixed upon opposite sides of the lamp-socket, suitable hooks fixed upon the hang-board and adapted to engage said lamp-hooks, and a detaching device pivoted to the hang-board and adapted to engage the lamp-hooks and release them from the hooks of the hang-board when the lamp is raised and lowered, substantially as described.

6. The combination, with the block A, adapted to be suspended from a support, as shown, and having openings A' and A² therein, and an inwardly-projecting hook a' adjacent to the opening A², the spring members b, fixed to the block above the hook a', having inwardly-extending beveled portions b' and an enlarged opening b², and a pulley B, pivoted in said block, of the hood D, the cord C, connected with the hood and extending over the pulley B, and the suspending-bar H, movable in the tube e of the hood, having at its upper end a hook H' to engage the hook a' and beveled portions b' of the members b, and having an angular bend H² below the tube e to limit 85 its downward movement, substantially as described.

7. The combination, with the hood D and hang-board D', and the sleeve F', having the slot F² and the terminal point F³, as shown, 95 of the suspending-rod G, adapted to move in the sleeve F', having a lug G' to engage the slot and guide the rod, and having a lamp-socket G² fixed to the lower end thereof, and means, as block A, pulley B, and cord C, for raising the rod, substantially as described.

8. The combination, with the hood D and hang-board D', the plates L, fixed to the lower portion of the hang-board and provided with inwardly-projecting hooks L', and the spring-actuated plates g, having the laterally-extending portions g' and parallel members g², the beveled portions g³, and the openings g⁴ therein, of the rod G, having the socket G² affixed thereto, and having means, as shown, for raising the same, and the spring-actuated rods M, pivoted to the upper portions of the socket G² and provided with outwardly-projecting hooks M' to engage the hooks L', substantially as described.

9. The combination, with the rod G, having means, as shown, for raising the same, and having the socket G² affixed to the lower end thereof, the upwardly-extending rods M, pivoted to the socket and provided with outwardly-extending hooks M', the plates L, fixed to the hang-board D' and having inwardly-projecting hooks L', which engage the hooks M', and the spring-actuated plates g, having the laterally-extending portions g', the parallel 125 members g², the beveled portions g³, and the openings g⁴ therein, of the spring-actuated slide J, adapted to move in the sleeve K, engage the upper end of one of the rods M and limit its upward movement, and the spring-actuated 130 stop J⁴, pivoted upon the hang-board D' and adapted to engage the upper end of the other rod M, substantially as described.

10. The combination, with the plates L,

fixed to the hang-board D' and provided with hooks L', as shown, and the spring-actuated plates g, pivoted upon the plates L and adapted to guide the lamp-hook rods, as shown, and 5 having upon their inner and upper edges the beveled portions g⁴, of the brushes i, adapted to engage the beveled portions of the plates g, the plates i', fixed to the hang-board D'

and adapted to support the brushes i, and the wires i², connecting the plates i' and the plates 10 L, to close the circuit, substantially as described.
